FIG. 5.

JAMES J. ANKER,
INVENTOR.

BY *William A. Hirtle*

ATTORNEY.

UNITED STATES PATENT OFFICE.

JAMES J. ANKER, OF VERONA, PENNSYLVANIA.

PHONOGRAPH ATTACHMENT.

1,374,483.

Specification of Letters Patent. Patented Apr. 12, 1921.

Application filed April 3, 1918. Serial No. 226,536.

To all whom it may concern:

Be it known that I, JAMES J. ANKER, a citizen of the United States of America, residing at Verona, in the county of Allegheny and State of Pennsylvania, have invented certain new and useful Improvements in Phonograph Attachments, of which the following is a specification.

The present invention relates to improvements in attachments for phonographs, and more particularly to the means for manipulating the reproducer heads of such machines. For the purpose I have devised a specially constructed spider adapted to be attached to the standard types of phonographs in current use, as will be fully described hereinafter in this specification.

In the accompanying drawings forming part of this specification I have illustrated one complete example of the physical embodiment of my invention constructed according to the best mode I have so far devised for the practical application of the principles of my invention.

Figure 1 is a top plan detail view of my invention.

Fig. 2 is a front elevational view of Fig. 1.

Fig. 3 is a rear or reverse view of the same.

Fig. 4 is a top plan view of a portion of the tone arm, reproducer head and connected parts of a phonograph showing my invention in operative position thereon.

Fig. 5 is a front elevational view of Fig. 4.

In the drawings the numeral 1 indicates the swinging tone arm of a phonograph, 2 the elbow or goose-neck member which is revolvably attached to the tone arm 1 at point 3, in the usual manner on such machines. 4 indicates the reproducer head having the usual diaphragm 5, stylus holder 6, and stylus 7.

The specially constructed spider 8 which I have devised is clearly illustrated in detail in the Figs. 1 to 3 inclusive of the drawings, and the method of attachment to the reproducer head, or sound box 4, is shown in Figs. 4 and 5. The spider 8 is made preferably of aluminum or similar light metal, and consists of a disk-like central portion 9, and a number of radially disposed arms 10, 11, 12, branching out therefrom. Each of the said arms 10, 11, etc., is provided with bent ends, substantially in the U-form as shown, and are designed to pass over the peripheral edge 13 of the reproducer

head 4, and form returned portions 14, 15, 16 having holes 17 in each. The holes 17 are made of proper size to accommodate the usual screws 18 which are a regular part 60 of the reproducer head 4, so that no changes are required in attaching my spider 8 to the ordinary reproducer head of the standard types of phonographs in current use. It is further observed that the arms 10, 11, 65 etc., have sufficient depth at 19, so that they do not interfere with the parts 20, 21, etc., which are part of the reproducer or sound box head 4, the importance of which is readily appreciated.

The spider 8 is also provided with a lifting button 22, preferably having a milled edge 23, and loosely and rotatably mounted on the disk-like center 9 for a purpose stated below. Two washers 24, 25 are provided 75 one on each face of the part 9 to take up the "wear" of the rotation of the button 22, and also to provide the requisite rigidity to the center of the spider, as the latter is made of very thin and light metal and hence 80 requires a certain amount of reinforcement at this point.

From the above it is believed the use of the device is obvious. When it is desired to disengage the stylus 7 from the record (not 85 shown) the lifting button 22 forms a convenient and definite point at which to attach the fingers, and the reproducer head 4, and elbow 2 are swung about points 3 manually until the head 4 rests on top of the tone 90 arm 1, in the position shown dotted at 26, Fig. 5 of the drawing. In placing the stylus in the grooves of the record (not shown) it is evident also that the stylus can be placed gently therein, so that the record itself is 95 not in the least injured, due to the ease of manipulation of the reproducer head 4 attained by the use of my invention. This last matter is one of importance when using high priced operatic and other records, and 100 the life of the records is also lengthened, by using my device. It is seen that by having the button 22 rotatably mounted on the spider 8 the necessity of revolving the fingers and hand is obviated when the elbow member and reproducer head are manipulated, and this is an advantageous feature of the device.

From the above description it is seen that I have provided a simple, practical, and inexpensive device for the purpose specified, 110 which may be readily attached to the stand-

ard types of phonographs in current use, and the utility of which is unquestioned.

What I claim is:—

A reproducer head lifting device comprising a spider having a freely rotatable lifting button thereon centrally positioned with reference to the reproducer head for the purpose of insuring smooth operation of the

latter when revolved about a pivotal point on the tone arm of a phonograph.

In testimony whereof I affix my signature in the presence of two witnesses.

JAMES J. ANKER.

Witnesses:

DAVID STONECIPHER,

WILLIAM A. HIRTLER.
